UNITED STATES PATENT OFFICE.

WILLARD C. JAMES, OF LOS ANGELES, CALIFORNIA, ASSIGNOR TO FRANK L. BELKNAP, OF CHICAGO, ILLINOIS.

BEDROOM FURNITURE.

1,354,615.

Specification of Letters Patent.

Patented Oct. 5, 1920.

Application filed September 15, 1913, Serial No. 789,907. Renewed June 5, 1920. Serial No. 386,924.

To all whom it may concern:

Be it known that I, WILLARD C. JAMES, a citizen of the United States, residing at Los Angeles, in the county of Los Angeles 5 and State of California, have invented new and useful Bedroom Furniture, of which the following is a specification.

This invention relates to furniture for various buildings, as hotels, private residences, apartment houses and other houses in which it is desirable to change a living room, reception room, dining room, work room or the like to a sleeping room as occasion requires; and an object is to provide 15 bedroom accommodations in such a room adapted for one or two persons occupying one bed or separate beds and to store such bedroom accommodations in a place of concealment with great ease and convenience 20 in a compact and comparatively small space behind a screen, as within a closet.

An object of the invention is to provide a convenience for drummers who usually display their goods on beds in their sleeping 25 rooms, and who consequently are put to the trouble of moving their goods from the bed when they wish to retire; and an object is to make provision whereby a drummer occupying a room provided with this invention 30 will have one concealable support as a table or bed upon which to make his display and another support in the form of a bed which may be concealed during the display and may be brought out of concealment and 35 put to use as occasion requires, thus allowing the drummer to occupy the bed in the same room with the display without disturbing such display, all of this being done if so wished, by an installation which is 40 very desirable for use where the room is to be occupied at night by two persons who do not wish to sleep together.

A further object is to provide means whereby the concealable furniture of a bedroom may be easily changed for accommodation of persons of various tastes and to supply various demands.

Also to adapt the concealed bed installation for interchange of beds from apartment 50 to apartment.

The invention may be carried out in various ways and I regard it as broadly new and pioneer in that I provide a screen, as a single cabinet or closet having a doorway 55 and means, as two sets of swinging bracket

means pivotally mounted on an unshifting vertical axis behind the screen, as in a closet, and a bed and a bedroom accessory device as a bed, a table, a dresser or the like mounted on the swinging brackets respectively; 60 whereby either or both of two beds or a bed and a bedroom accessory may be compactly stored at any time, and either or both of the beds or the bed and the accessory may be brought into use at pleasure. 65

The beds with which this invention is best applied are double, single or three quarter up-endable beds and where twin beds are used they are preferably stored adjacent each other in up-ended condition in a closet 70 having a doorway of ordinary width.

Where single beds are thus mounted they are usually of less width than the doorway through which they pass from use position to storage, and vice versa. 75

It is thought that the invention may be fully understood by illustration of the twin bed and the bed and dresser installations since in the one instance one of the beds, and in the other instance the dresser may 80 serve as a table and although the dresser from its nature may not be foldable or up-endable, the table proper may be so constructed in perfect accord with the principle of this invention. 85

The accompanying drawings illustrate the invention.

Figure 1 is a fragmental plan of a manufactured structure equipped with my newly-invented twin bed furniture; the beds being 90 in storage. Dash and dot lines indicate positions of the beds up-ended and swung out into the room for which the beds are adapted. Dotted lines indicate an intermediate position of the first or front bed. 95

Fig. 2 is an elevation partly in section on line x^2 , Figs. 1 and 3.

Fig. 3 is an elevation partly in section on line x^3 , Figs. 1 and 2.

Fig. 4 is a detail of the bed supporter with 100 fragments of a bedstead and a bracket arm.

Fig. 5 is a fragmental plan analogous to Fig. 1 in which a dressing case is shown substituted for one of the twin beds and the parts are adjusted for occupancy of the 105 room as a bedroom. Dot and dash lines indicate a stored position of the dressing case and bed.

Reference will now be made to the twin bed installation shown in Figs. 1, 2, 3 and 4. 110

A closet 1 may be provided at any suitable place adjoining the room 2 and is provided with a suitable doorway 3 and a door 4 that may be of any appropriate construction, either a sliding or swinging door; a swinging door being shown in the drawings. Pivotal supporting means are provided at a suitable place inside the closet as indicated by the axis 5, which is shown arranged close to one side of and in unshifting vertical relation to the doorway 3.

Two beds 6, 6' are provided to be stored in a position of concealment behind the screen formed by the wall of the closet, and means adapted to carry the bed from concealment in one position relative to the screen into stations for use in other positions relative to the screen, and vice versa, are provided as hereinafter described.

The two beds 6, 6' are similarly constructed and may be of any desirable up-ending form comprising an upright head-board 7 and an up-endable bedstead section 8 pivoted thereto by any suitable means as a connecting bar 9 and rod 10, and suitable pivots; the bar being pivoted to the head-board at 11 and to the up-endable bed section at 12, and the rod being pivoted to the head-board at 13 and to the up-endable bedstead section 8 at 14, allowing said section 8 to be turned down and up as usual with up-endable beds.

For convenience of description the beds 6, 6' are termed the rear and front or second and first beds respectively.

Said beds are respectively connected with the pivotal supporting means by bracket means shown in the drawings as a relatively short single-arm bracket and a relatively long multiple joint bracket respectively, there being one or more brackets for each bed; each single-arm bracket comprising a swinging bracket arm as at 15 and each multiple-joint bracket comprising a plurality of bracket arms as at 16, 17, pivotally connected together as by the axis 18. A set of two brackets is shown as the bracket means for each bed.

The arms 15 may be pivotally connected relative to the head-board 7 of the bed 6 by any suitable means as by the bed holder 19 which is shown pivoted at 20 to the end of the top bracket arm 15 and provided with a retainer in the form of a stud 21 seated in a hole 22 in the top rail of the head-board 7, which is thus removably mounted on the holder.

The multiple-joint bracket is connected with its bed 6' in substantially the manner just described, and by similar bed-holder means which are indicated in the drawings by similar reference characters with an index.

The rear bed 6 and its relatively short swinging bracket means are mounted to

swing to a position adjacent the wall 23 inside the closet when the bed is stored; and the bracket is constructed and arranged to swing around the door post or the edge of the wall to bring the bed to a station adjacent to the outside thereof, said wall practically forming a screen for the stored bed and for the storage chamber formed by the closet, and being one wall of the room 2. The front bed 6' and its bracket means are constructed and arranged to be stored adjacent the rear bed inside the closet, and the purpose of the multiple-joint bracket means is to allow the bed to be inserted into the narrow space between said rear bed and farther wall 24 of the closet; and to allow said front bed 6' to be readily drawn out and swung around adjacent the outside of the wall or screen 23.

The pivotal supporting axis 5 may be mounted in the closet by any suitable bearing means as by the seat 25 fixed to the floor 26, and the eye 27 fixed to an upper support as the wall of the closet.

In practice the building in which the invention is to be applied may be manufactured in any desired manner and the screen may be constructed as a closet wall or any other desirable screening element, either constructed with or independently of the building; and the pivotal means may be fixed to the building at the time it is manufactured or subsequently, or the pivotal means, brackets and beds may be installed in any closet or other available space in any building already manufactured.

It is evident that although I have shown the closet in the drawings as being quite well filled with the beds and their brackets, that the closet may be of any desired size and that the beds may be stored or made to stand therein in such position as to give access thereto to all parts of the walls of the storage space, these features being of such a nature that when once suggested to the ordinary constructor, they may be embodied without further invention, they are not illustrated in the drawings.

It is understood that the bed holder may be attached to the bedstead at any point thereon, care being taken that the construction is strong and rigid, so that the beds will swing freely into and out of position when up-ended, and to this end the bed 6 is shown connected near one edge to the end of the relatively short bracket and the bed 6' is shown connected to the end of its bracket practically mid-way between the edges of the bed.

The bracket arms 15 and 16 that are swung directly on the pivotal axis 5 are provided with bends 28, 29 respectively to accommodate the edge of the screen or closet wall. These bends may be of any suitable character to allow satisfactory movement of

the brackets in the operation of swinging the beds through the doorway and around the edge thereof out into desired position for use.

5 When the beds are in the dot and dash position shown in Fig. 1, or in any other non-interfering position in the room, they may be lowered for use in the customary manner, and when again up-ended the rear 10 bed 6 will first be swung in behind the screen, and then the front bed 6' will be swung into position adjacent thereto so that when the beds are in concealed or stored position, the headboards are at substantially 15 right angles to the open wall.

The operation of swinging the beds from the concealed or stored position, shown in solid lines in Fig. 1, to the exposed or used 20 position shown in dot and dash position in said figure is just the reverse of that just described.

In Fig. 5 a dressing case 30 is shown installed upon the bed holder 19' in place of one of the twin beds shown in Figs. 1 25 and 2. Preferably the dresser 30 is mounted on the front holder 19' in the place occupied in said figures by the front bed 6' so that the dresser may remain in the room 2 when the bed 6 is stored. It is 30 understood the form and the character of the room and screen may vary without changing the character of the invention and in Fig. 5 a window 31 not shown in the other views appears in the outside wall 32.

35 Said dressing case may be provided with a bracket 33 having a hole 34 in which the stud 21' of the bed-holder 19' is adapted to seat thus to support the case in a manner similar to the bed 6' shown in Fig. 1.

40 In this way the bed-room may be variously furnished as occasion requires by simply providing each article of furniture with a suitable mounting for the holders.

Thus it is seen that the bedsteads and 45 other articles of furniture may be of any desired construction or style and the style may be changed at will by simply lifting the article from its bracket and making the desired substitution.

50 I claim:—

1. The combination with a screen, of pivotal means arranged on an unshifting vertical axis, brackets mounted on said means and adapted to swing from one to 55 another position relative to the screen, and up-endable beds supported by the brackets respectively and adapted when up-ended to stand adjacent each other on one side of the screen and on a common level and also 60 adapted to swing with said brackets to another position for use on said common level.

2. The combination with a screen, of a relatively short bracket in pivotal relation to the screen and a relatively long bracket 65 in pivotal relation to said screen, said

pivotal relations being on an unshifting vertical axis and up-endable beds mounted on said brackets respectively, said beds when up-ended being storable adjacent each other on one side of the screen and on a 70 common level and adapted to be swung on said brackets into other positions relative to the screen and on said level for individual use when lowered.

3. The combination with a screen, of two 75 brackets arranged on an unshifting vertical axis in pivotal relation to the screen, one of said brackets being double-jointed and longer than the other bracket, and up-endable beds carried by the brackets respectively and storable adjacent each other on one side of the screen and on a common level and adapted to be carried by said brackets to other positions relative to the screen and relative to each other, so that they may be 80 85 brought into position for use adjacent each other and on said common level.

4. The combination with a screen, of two 90 brackets arranged on an unshifting vertical axis in pivotal relation to the screen, one of said brackets being double-jointed and longer than the other bracket, and up-endable beds carried by the brackets respectively and storable adjacent each other on one side of the screen and adapted to be 95 carried by said brackets to other positions relative to the screen and relative to each other, so that they may be brought into position for use side by side of each other; said brackets having bent arms to accommodate 100 the edge of the screen.

5. The combination with a screen, of two single brackets pivotally arranged on an unshifting vertical axis, one of the brackets having an arm bent to accommodate the 105 edge of the screen, and beds on said brackets respectively, said beds being carried by said brackets and individually moved therewith to positions of storage and use upon opposite sides of said screen and 110 on a common level.

6. The combination with a screen, of two articles of furniture adapted to be stored behind the screen, and brackets of different 115 lengths, said brackets being pivotally arranged on an unshifting vertical axis and forming the carrying means for said articles of furniture whereby the latter may be stored adjacent to each other on one side of the screen, and when positioned upon 120 the other side of the screen may be in alignment.

7. The combination with a screen having corner walls and a door opening in one of the walls, of pivotal means arranged on an 125 unshifting vertical axis adjacent to said opening; brackets mounted on said means and adapted to swing from positions inside of said screen through said opening around one edge thereof to positions outside of the 130

- screen; and upendable beds respectively supported by said brackets; said beds when upended being adapted to stand adjacent to each other inside of the screen with their headboards at substantially right angles to the open wall, and to swing with said brackets through the door opening and around said edge into positions for use outside of said screen.
10. 8. The combination with a screen having corner walls and a door opening in one of the walls, of pivotal means arranged on an unshifting vertical axis adjacent to said opening; a relatively short bracket and a 70 relatively long bracket mounted on said means; and upendable beds respectively supported by said brackets, said beds when upended being storable adjacent to each other inside of the screen with their headboards at substantially right angles to the open wall, and adapted to swing with said brackets through said opening and around one edge thereof into positions adaptable for the use of said beds when lowered outside of said screen.
15. 9. The combination with a screen having corner walls and a door opening in one of the walls, of pivotal means arranged on an unshifting vertical axis adjacent to said opening; two swinging brackets mounted on said means; one of said brackets having an 75 arm bent to accommodate one edge of the door opening and a corner of the screen; beds respectively supported by said brackets; said beds being adapted to stand adjacent to each other inside of the screen with their headboards at substantially right angles to the open wall, and to swing with said brackets through the door opening and around one edge thereof into positions for use outside of said screen.
20. 10. The combination with a screen having corner walls and a door opening in one of the walls, of pivotal means arranged on an unshifting vertical axis adjacent to said opening; two brackets mounted on said means; one of said brackets being double-jointed and longer than the other bracket; and upendable beds respectively supported by said brackets, said beds when upended 80 being storable adjacent to each other inside of the screen with their headboards at substantially right angles to the open wall, and adapted to be carried by said brackets through said opening and around one edge thereof so that they may be brought into positions adaptable for the use of said beds adjacent to and in alignment with each other.
25. 11. The combination with a screen having corner walls and a door opening in one of the walls, of pivotal means arranged on an unshifting vertical axis adjacent to said opening; two brackets mounted on said means, one of said brackets having bent 85 arms to accommodate one edge of the opening and the corner of the screen; and one of said brackets being double-jointed and longer than the other bracket; and upendable beds respectively supported by said brackets; said beds when upended 90 being storable adjacent to each other inside of the screen with their headboards at substantially right angles to the open wall, and adapted to be carried with said brackets through the door opening and around one edge thereof into positions for use outside of said screen.
30. 12. The combination with a screen having corner walls and a door opening in one of the walls, of pivotal means arranged on an unshifting vertical axis adjacent to said opening; two swinging brackets mounted on said means; one of said brackets having an 95 arm bent to accommodate one edge of the door opening and a corner of the screen; beds respectively supported by said brackets; said beds being adapted to stand adjacent to each other inside of the screen with their headboards at substantially right angles to the open wall, and to be moved individually with said brackets through the door opening and around one edge thereof into positions for use outside of said screen.
35. 13. The combination with a screen having corner walls and a door opening in one of the walls, of pivotal means arranged on an unshifting vertical axis adjacent to said opening; brackets of different lengths 100 mounted on said means; two articles of furniture having faces supported by the respective brackets; said articles being storable adjacent to each other inside of the screen and on a common level with their supported faces at substantially right angles to the open wall while they are thus supported.
40. 14. The combination with a screen having corner walls and a door opening in one of the walls, of pivotal means arranged on an unshifting vertical axis adjacent to said opening; brackets of different lengths 105 mounted on said means; two articles of furniture having faces supported by the respective brackets; said articles being storable adjacent to each other inside of the screen with their supported faces at substantially right angles to the open wall, and adapted to be carried with said brackets through the door opening and around one edge thereof into positions with their supported faces in alignment with each other.
45. 15. The combination with a screen having corner walls and a door opening in one of the walls, of pivotal means arranged on an unshifting vertical axis adjacent to said opening; brackets of different lengths 110 mounted on said means; beds respectively supported by said brackets; said beds being storable adjacent to each other inside of the screen with their supported faces at substantially right angles to the open wall, and adapted to be carried with said brackets through the door opening and around one edge thereof into positions with their supported faces in alignment with each other.
50. 16. The combination with a screen having corner walls and a door opening in one of the walls, of pivotal means arranged on an unshifting vertical axis adjacent to said opening; brackets of different lengths 115 mounted on said means; beds respectively supported by said brackets; said beds being storable adjacent to each other inside of the screen with their supported faces at substantially right angles to the open wall, and adapted to be carried with said brackets through the door opening and around one edge thereof into positions with their supported faces in alignment with each other.
55. 17. The combination with a screen having corner walls and a door opening in one of the walls, of pivotal means arranged on an unshifting vertical axis adjacent to said opening; brackets of different lengths 120 mounted on said means; beds respectively supported by said brackets; said beds being storable adjacent to each other inside of the screen with their supported faces at substantially right angles to the open wall, and adapted to be carried with said brackets through the door opening and around one edge thereof into positions with their supported faces in alignment with each other.
60. 18. The combination with a screen having corner walls and a door opening in one of the walls, of pivotal means arranged on an unshifting vertical axis adjacent to said opening; brackets of different lengths 125 mounted on said means; beds respectively supported by said brackets; said beds being storable adjacent to each other inside of the screen with their supported faces at substantially right angles to the open wall, and adapted to be carried with said brackets through the door opening and around one edge thereof into positions with their supported faces in alignment with each other.
65. 19. The combination with a screen having corner walls and a door opening in one of the walls, of pivotal means arranged on an unshifting vertical axis adjacent to said opening; brackets of different lengths 130 mounted on said means; beds respectively supported by said brackets; said beds being storable adjacent to each other inside of the screen with their supported faces at substantially right angles to the open wall, and adapted to be carried with said brackets through the door opening and around one edge thereof into positions with their supported faces in alignment with each other.

headboards at substantially right angles to the open wall, and adapted to swing the said brackets through said opening and around one edge thereof into other positions outside 5 of said screen and on said common level.

16. The combination with a screen having corner walls and a door opening in one of the walls, of pivotal means arranged on an unshifting vertical axis adjacent to said 10 opening; a plurality of brackets mounted on said means; a plurality of furniture articles having faces supported by the respective brackets; said articles being successively storable adjacent to one another inside of 15 the screen and on a common level, with their supported faces at substantially right angles to the open wall, while said articles are thus supported by said brackets and the brackets are mounted on said pivotal axis.

20 17. The combination with a screen having corner walls and a door opening in one of the walls, of pivotal means arranged on an unshifting vertical axis adjacent to said

opening; a plurality of brackets mounted on said means; a plurality of furniture articles 25 having faces supported by the respective brackets; said articles being storable singly or successively in multiple adjacent to one another inside of the screen and on a common level, with their supported faces at substantially right angles to the open wall, and 30 adapted to swing with said brackets through the door opening and around one edge thereof into positions for use outside of said screen and on said common level, and vice 35 versa, while said articles are thus supported by said brackets and the brackets are mounted on said pivotal axis.

In testimony whereof, I have hereunto set my hand at Los Angeles, California, this 40 10th day of September, 1913.

WILLARD C. JAMES.

In presence of—
JAMES R. TOWNSEND,
L. BELLE WEAVER.
